UNITED STATES PATENT OFFICE.

ALFRED E. STAFFORD, OF HOPEDALE, MASSACHUSETTS, ASSIGNOR TO DRAPER CORPORATION, OF HOPEDALE, MASSACHUSETTS, A CORPORATION OF MAINE.

TRANSFER MECHANISM FOR LOOMS.

1,427,421.

Specification of Letters Patent Patented Aug. 29, 1922.

Application filed February 24, 1920. Serial No. 360,892.

To all whom it may concern:

Be it known that I, ALFRED E. STAFFORD, a citizen of the United States, and resident of Hopedale, county of Worcester, State of Massachusetts, have invented an Improvement in Transfer Mechanisms for Looms, of which the following description, in connection with the accompanying drawing, is a specification, like characters on the drawing representing like parts.

This invention relates to improvements in transferring mechanisms for automatic filling replenishing looms and the object thereof is to provide means for permitting the 15 transerrer to yield when an abnormal obstruction is encountered by the transerrer arm or head.

In the operation of looms the shuttle occasionally becomes misplaced in the shuttle 20 box, either by rebounding from the picker stick or by being arrested before it has reached its proper seat in the shuttle box. When the shuttle is thus misplaced at the 25 time the transfer is called for, the transerrer strikes vigorously against the shuttle, the force being sufficient at times to smash the shuttle or to break the transerrer arm, or occasionally to break the hopper stand.

The object of the present invention is to 30 provide means for preventing accidents of this character by introducing a yielding instrumentality into the means for actuating the transerrer, said resilient means being of sufficient strength to enable the trans- 35 ferrer properly to transfer the filling carrier from the hopper into the shuttle with certainty, but which will yield when any abnormal obstruction is encountered.

Another object of the invention is to pro- 40 vide means whereby the force of the resilient instrumentality may be adjusted.

Other objects and features of the invention will more fully appear from the following description and the accompanying 45 drawings and will be pointed out in the annexed claims.

A preferred embodiment of the invention is disclosed herein as applied to the transferring mechanism of an automatic filling 50 replenishing loom of the well known Northrop type, a sufficient portion of the loom being shown to identify the novel transferring mechanisms therewith.

In the drawings:

Fig. 1 is an elevation, partly in cross sec-

tion, of so much of an automatic filling replenishing loom of the Northrop type as is necessary to a disclosure of the present invention, with the preferred form of the invention embodied therein.

Fig. 2 is a sectional view on line 2—2 Fig. 1 showing the pivotal mounting for the transerrer.

Fig. 3 is a detail end view of the transerrer looking from the left toward the right 65 of Fig. 1.

The present invention, which involves the introduction of means which will permit the transerrer to yield when an abnormal obstruction is encountered, is illustrated herein as applied to the well known Northrop type of loom which comprises a frame or loom side 1, to one end of which is secured a hopper stand 2, upon which is mounted a rotary hopper 3 having peripheral recesses 4 which support the fresh filling carriers 5 which are to be introduced in the shuttle.

The lay 6 is of the usual construction and is provided with a shuttle race and shuttle box to receive the shuttle 7 which is actuated by the usual picker mechanism. The lay 6 is provided at the transerrer end of the loom with an opening through which the old filling carrier may be discharged when a new filling carrier is introduced in the 85 shuttle.

A transerrer 8 is pivotally mounted upon a transerrer stud 9 which extends laterally from the hopper stand and is provided at one end with a head 10 preferably having a curved face adapted to engage the fresh filling carrier and thrust the same from the hopper into the shuttle upon call for trans- 90 fer.

In the usual transferring mechanism the transerrer comprises a bell crank lever having one arm provided with a head to engage the filling carrier and another arm extending substantially at right angles to it to which is pivoted a dog which, upon call for transfer, is raised in the path of a bunter upon the lay so that as the lay beats up, the transerrer is rocked about its pivot causing the head to be forced downward in such a manner as to thrust a properly positioned filling carrier from the hopper into the shuttle, at the same time expelling the old filling carrier from the shuttle. If at the time the transerrer is thus operated, the shuttle is misplaced, or if some other obstruction is 110

presented, a smash is likely to occur since the transferrer is of rigid construction and is actuated by the movement of the rigid bunter upon the lay.

5 The present invention contemplates the introduction of yielding means intermediate of the transferrer and its actuating means which, while of sufficient strength to insure the proper operation of the transferrer, will 10 permit the transferrer to yield when an abnormal obstruction is encountered and thereby avoid breakage of the transfer arm which sometimes occurs, or breakage of the hopper stand itself which has been known to occur 15 from such causes in a few instances.

Any yielding mechanism for accomplishing this purpose may be introduced within the spirit and scope of the present invention. In the preferred mechanism which is disclosed herein the transferrer 8, instead of having a rigid actuating arm, is provided with an arm having a bifurcated end provided with laterally extending integral members 11 and 12 which are connected by an integral bridge 13. The member 12 may also desirably be provided with a boss 14 providing a seat for an adjusting screw 15 which may be clamped in adjusted position by a set nut 16. In this construction the hub of 30 the transferrer, instead of being mounted directly upon the stud 9, is in the form of a sleeve 17 integral with the arm 8 and of sufficient size to enclose and fit upon the reduced portion 18 of the hub of an actuating arm 19 which is pivotally mounted upon the transferrer stud 9.

The arm 19 is provided with a laterally extending lug 20 which projects into a recess 21 of the bifurcated actuating arm of the transferrer. The lug 20 is provided with a central stud 22 which extends within the coil of the helical spring 23, one end of which is seated upon the stud 22 and the other end of which abuts against the flat end of the adjusting screw 15 which preferably has a lug 24 also projecting into the coil of the spring 23. The helical spring 23 is assembled in the construction under sufficient compression to hold the lug 20 of the actuating arm 19 firmly against the member 11 of the transferrer so that the actuating arm 19 will be permitted to yield only when the transferrer encounters a substantially non-yielding obstruction.

55 The actuating arm 19 is provided with the usual bifurcated end 25 upon which the dog 26 is pivoted. Any usual controlling mechanism may be employed for raising the dog 26 into the path of the bunter 27 which is carried by the lay upon call for transfer, but as such controlling mechanism is well known it is not illustrated herein.

In the normal operation of the loom the transferrer operates in the usual manner, 60 the dog 26 being raised into the path of the

bunter upon call for transfer, the engagement of the bunter rocking the actuating arm 19 and transferrer 8 about the axis of the transferrer stud 9 so that the head 10 engages the base of a fresh filling carrier 70 and thrusts it into the shuttle, the entering filling carrier displacing the old filling carrier from the shuttle and taking its place. When, however, the shuttle is misplaced or some other abnormal obstruction lies in the path of the transferrer arm the spring 23 will permit the transferrer to yield relatively to the actuator so that the latter may have its full movement without causing breakage or damage to the transferrer or to its support.

The adjusting screws 15 may be so adjusted as to impose any desired degree of compression upon the spring 23 and when adjusted may be locked in the desired position by the set nut 16.

It will be understood that the embodiment of the invention disclosed herein is illustrative and not restrictive and that the invention may be employed in other types of looms, and that various changes in construction, size and arrangement of parts may be made within the spirit and scope of the following claims.

Having thus described my invention, what I claim as new and desire to secure by Letters Patent, is:

1. An automatic filling replenishing loom comprising a transferrer, means operable by the movement of the lay to positively 100 actuate the same including a compression spring acting to permit said transferrer to yield upon encountering an abnormal obstruction.

2. An automatic filling replenishing loom 105 comprising a pivotally mounted transferrer, transferrer actuating means operable by the movement of the lay and a compression spring interposed between said actuating means and said transferrer acting to permit 110 said transferrer to yield upon encountering an abnormal obstruction.

3. An automatic filling replenishing loom comprising a pivotally mounted transferrer, transferrer actuating means operable by the 115 movement of the lay and a compression spring interposed between said actuating means and said transferrer acting to permit said transferrer to yield upon encountering an abnormal obstruction and means for adjusting the compression of said spring.

4. An automatic filling replenishing loom comprising a hopper stand and hopper, a transferrer stud on said hopper stand, a transferrer pivotally mounted upon said 125 transferrer stud, a transferrer actuating arm pivotally mounted on said transferrer stud, means for oscillating said transferrer actuating arm and resilient means interposed between said actuating arm and said trans-

ferrer acting to permit said transferrer to yield upon encountering an abnormal obstruction.

5. An automatic filling replenishing loom comprising a hopper stand and hopper, a transferrer stud on said hopper stand, a transferrer pivotally mounted upon said transferrer stud, a transferrer actuating arm pivotally mounted on said transferrer stud, 10 means for oscillating said transferrer actuating arm, a compression spring interposed between said transferrer actuating arm and said transferrer acting to permit said transferrer to yield upon encountering an abnormal 15 obstruction and means for adjusting the compression of said spring.

6. An automatic filling replenishing loom comprising a hopper stand and hopper, a transferrer stud upon said hopper stand, a 20 transferrer in the form of a bell crank lever pivotally mounted upon said stud, one arm of said transferrer having a head to engage the filling carrier, the other arm of said 25 transferrer being bifurcated, a transferrer actuating arm having means located within the bifurcation of said transferrer arm, and

resilient means interposed between said actuating arm and one of the members of said bifurcated transferrer arm acting normally to retain said actuating arm against the 30 other member of the bifurcated arm of the transferrer, but adapted to yield when the head of the transferrer engages an abnormal 35 obstruction.

7. An automatic filling replenishing loom comprising a hopper stand and hopper, a transferrer stud on said hopper stand, a transferrer in the form of a bell crank lever pivotally mounted upon said stud, one arm of said transferrer having a head to engage 40 the filling carrier, the other arm being bifurcated and provided with a yoke overlying said bifurcation, an actuating arm pivotally mounted on said stud having a lug extending into said bifurcation, a helical 45 spring interposed between one member of the bifurcated arm of said transferrer and said lug and means for adjusting the compression of said spring.

In testimony whereof, I have signed my name to this specification.

ALFRED E. STAFFORD.
